[57] CLAIM

The ornamental design for a Christmas tree watering ornament, as shown and described.

DESCRIPTION

FIG. 1 is a right side elevational view of a Christmas tree watering ornament showing our new design, the broken-line disclosure of a Christmas tree, hook and watering can being for illustrative purposes only and forming no part of the claimed design;

FIG. 2 is an enlarged top, rear, and right side perspective view thereof;

FIG. 3 is an enlarged front elevational view thereof;

FIG. 4 is an enlarged left side elevational view thereof;

FIG. 5 is an enlarged rear elevational view thereof; and,
FIG. 6 is an enlarged top plan view thereof.

The tube portion in the enlarged views is shown broken-away for convenience of illustration.
